PAUL J. SIMMEN, OF EDEN, NEW YORK

TRAIN-CONTROL SYSTEM

Application filed September 26, 1921, Serial No. 503,235. Renewed May 26, 1928.

This invention relates to train control systems and more particularly to a system which involves the co-ordination of central office apparatus, means for establishing different circuit conditions and devices severally responsive to the circuit conditions and employed for the regulation or control of train movements.

The features of improvement, broadly stated, severally relate first to the recording at the central office of the movements of trains in relation to particular devices for regulating such movements, second, to the selection at the central office of different cab circuit conditions to which the train movement controlling devices are severally responsive, third, to the co-ordination of the recording at the central office of the movements of trains in relation to particular devices for regulating such movements and the selection at the central office of the operation of such particular devices, and fourth, to the co-ordination by a single selective operation of the cab circuit conditions of two trains moving in opposite directions on the same track whereby a circuit condition in one train which will produce the operation of a particular regulating device for that train will be concomitant with another circuit condition in the opposing train and which will produce the operation of another particular regulating device for the opposing train and which is appropriate to the operation of the device for the regulation of the first train.

The invention also consists of various details of structure and combination appurtenant to the several features of improvement above stated.

The general objects of the invention are to provide a greater flexibility and capacity in the regulation of train movements from the central office, to provide greater detail and certainty in the recording of train movements and train movement regulating operations at the central office, to reduce to a minimum the necessity for telephonic communication between the engineer or motorman and the despatcher and likewise to reduce to a minimum the issuance of orders or

directions by telephone or telegraph, and in general to give the despatcher greater and more certain control of traffic conditions and greater and more certain continuous and instant information as to such traffic conditions, thereby to combine facility of operation, i. e. the greatest economy of track capacity, with safety of operation.

An illustrative embodiment of the invention is disclosed in the accompanying drawings, wherein:

Figure 1 is a diagram showing the apparatus at the despatcher's office in relation to the track of the railroad.

Figure 2 is a diagram showing the cab circuits and equipment.

Figure 3 is a side elevation of one of the despatcher's operating switches.

Figure 4 is a rear elevation of the same. The devices for regulating train movements are preferably signals and are further preferably located in the cab.

For the transmission of the signal currents I preferably use, in accordance with known practice, short third rails or ramps. Along the track 1, which may be assumed to run east and west, are a number of stations A, B, C, D, E, etc., which may be actual stations or other convenient dividing points between blocks, station A being assumed to be a terminal of the road or of a division thereof. At each station there is a siding 2, which in the diagram of Figure 1 is shown disproportionately large in relation to the distance between two adjacent stations or blocks. The signal rails are also provided at each station and preferably and in accordance with known practice are connected in pairs, each pair comprising a "home" rail 3 and a "distant" rail 4, these rails being provided for each direction of train movement and conveniently located on the right hand side of the track. The car or locomotive indicated diagrammatically by the showing of the truck T is provided with a movable shoe 5 for engagement with the signal rails whose arrangement is such that the shoe 5 will first engage the distant rail and thereafter the home rail.

The different cab circuits are controlled by

- different electrical conditions of the rails 3 and 4. These electrical conditions involve the use of currents of different characteristics, e. g. alternating and direct currents.
- 5 As shown and preferred the electrical conditions are obtained by a combination of alternating and positive direct current, a combination of alternating and negative direct current, positive direct current only, negative direct current only, alternating current only, and the absence of electrical energy.
- The cab circuits and the devices for regulating the train movements, in the present instance signal lamps, are shown in Figure 15 2. The car carries relays A R and D R which are used to control the operation of such lamps. The relay A R is double wound, that is to say it has a coil 39 which is energized by alternating current and a holding coil 40 which is energized by direct current. This relay also has two armatures 41 and 42 which are in the upper position, as shown, when either of the coils 39 or 40 is energized but move to their lower positions when both of 25 the coils are deenergized. The relay D R has armatures 43, 44 and 45 which, when the relay is energized, are in the upper positions as shown but when the relay is de-energized are in their lower positions. The relay D R also 30 includes polarized armatures 46, 47, 48 and 49. These armatures swing from left to right as viewed in the drawing. When the relay D R is energized positively, that is to say when the current enters relay D R by the 35 wire 50, then all of the armatures 46 to 49 inclusive swing to the left to the positions as shown in the drawing. When, however, the relay D R is negatively energized, that is to say, when the current leaves by the wire 50, then all the armatures 46 to 49 inclusive 40 swing to right hand positions, corresponding to the left hand positions as shown in the drawing. To insure the operation of the coil 39 of relay A R only by alternating current a condenser 51 is inserted between the wires 45 52 and 53; and to insure the operation of the relay D R only by direct current an impedance coil 54 is inserted between the wires 50 and 55.
- 50 For the control of the circuits of certain of the lamps, as hereafter pointed out in detail, I provide a four-pole double throw switch S whose arms may be assumed to be in the right 55 hand position on east bound trains and in the left hand position on west bound trains. The switches S of opposing trains insure that the energy in a signal rail which will produce the operation of a particular regulating device in an east bound train will produce in a west bound train the operation of a different regulating device, appropriate however to the operation produced in the east bound train. In other words the switch S provides 60 for an automatic bilateral selection of regu- 65 lating devices which will co-ordinate the movements of such trains.
- Assuming that alternating current is supplied to a signal rail, the car T is advancing with its shoe 5 in contact with such rail and the signal rail and a rail of the track 1 are terminals of the generator, under such conditions the alternating current will flow by the signal rail, the shoe 5, the wire 53, condenser 51 and wire 52 through coil 39 of relay A R and thence by wires 39^a and 57 to a rail of the track 1 (i. e. through the axle and wheel of the car). The resultant energization of relay A R causes armatures 41 and 42, if in their lower positions, to be raised, or, if already raised, to be held in raised positions. Each signal rail is, as usual, inclined on both ends and this permits shoe 5 gradually to lower as the car T passes, whereby the insulated metallic plate 60 mounted on the shoe connects wires 61 and 62 before the shoe actually leaves the ramp. The connection of wires 61 and 62 by the shoe 5 while the armature 41 is in a raised position causes a stick circuit to be formed through the coil 40 of the relay A R, which circuit maintains the relay A R energized until the advancing car T causes the shoe 5 to contact with another signal rail. This stick circuit is as follows, the diagram of Figure 2 being also considered and it being assumed that the last previous energization of the relay D R was positive: One terminal of battery 68, wires 69 and 70, armature 47 in the left hand position, wires 71 and 65, armature 41 in a raised position, wire 62, plate 60, wire 61, coil 40, wires 64, 57, 66 and 73, armature 46 in the left hand position and wire 74 to the other terminal of battery 68. If, however, the last previous energization of the relay D R was negative the stick circuit is traced in the opposite direction and through the armatures 46 and 47 in their right hand positions, that is to say, one terminal of battery 68, wire 69, armature 46 in the right hand position, wires 73, 66, 57 and 64, coil 40, wire 61, plate 60, wire 62, armature 41, wires 65 and 71, armature 47 in the right hand position and wire 74 to the other terminal of battery 68.
- Assuming that the signal rail is positively energized and in contact with the shoe 5 of the advancing car T and that said signal rail and a rail of the track 1 are battery terminals, direct current will flow through the relay D R entering by wire 50. The circuit is as follows: signal rail, shoe 5, wires 53 and 55, impedance coil 54, wire 50, relay D R and wire 66 to track rail 1. As the car passes beyond the ramp the shoe 5 will make contact with the wire 67 so that, the armature 43 being in a raised position, a stick circuit for relay D R will be formed as follows: one terminal of battery 68, wires 69 and 70, polarized armature 47 in the left hand position by reason of the previous positive energization

of the relay D R, wires 71 and 72, armature 43, wire 67, shoe 5, wires 53 and 55, impedance coil 54, wire 50, relay D R, wires 66 and 73, polarized armature 46 in the left hand position and wire 74 to the other terminal of battery 68. Assuming that the signal rail is negatively energized and in contact with the shoe 5 of the advancing car T and that said signal rail and a rail of the track 1 are battery terminals, direct current will flow through the relay D R, entering by the wire 66. In such a case the circuit will be as follows: from the rail 1, thence through wire 66, relay D R, wire 50, coil 54, wires 55 and 53 and shoe 5 to signal rail. The stick circuit which becomes effective when shoe 5 leaves the ramp is as follows: one terminal of battery 68, polarized armature 46 in the right hand position by reason of the previous negative energization of relay D R, wires 73 and 66, relay D R, wire 50, coil 54, wires 55 and 53, shoe 5, wire 67, armature 43 in its raised position, wires 72 and 71, armature 47 in the right hand position and wire 74 to the other terminal of battery 68.

It will, of course, be understood that whether relay D R is energized positively or negatively, the armatures 43, 44 and 45 will be in the upper positions and it will be only when relay D R is not energized at all that these armatures are in the lower positions. It will also be understood that polarized armatures 46 to 49 inclusive will remain in the positions to which they have last been moved until the relay D R has been reversely energized.

The cab circuits described provide for six different circuit conditions pursuant to which six phases of train movement regulation, each responsive to a particular circuit condition, may be utilized in the embodiment disclosed. As shown the train movement regulating devices consist of signal lamps which may have any desired significance. The lamps are designated 76 to 81 inclusive and in the present diagram respond to cab circuit conditions established in the following order, namely, the lamp 76 of an east bound train when alternating and positive direct current is supplied to the signal rail, and of a west bound train when alternating and negative direct current is supplied, the lamp 77 of an east bound train when alternating and negative direct current is supplied to the signal rail, and of a west bound train when alternating and positive direct current is supplied, the lamp 78 of an east bound train when positive direct current only is supplied to the signal rail, and of a west bound train when negative direct current only is supplied, the lamp 79 of an east bound train when negative direct current only is supplied to the signal rail, and of a west bound train when positive direct current only is supplied, the lamp 80 of an east or west bound train when alternating

current only is supplied to the signal rail and the lamp 81 of an east or west bound train when the signal rail is de-energized. It is further to be noted that the circuits of the lamps 76 to 79 inclusive are completed by the reversing switch in either position of its arms. As stated, the signal lamps may have any desired significance and for the purpose of illustration colors and meanings may be assigned to them as follows: lamp 76, green for "clear," lamp 77, red for "stop—no right of way," lamp 78, purple for "take siding," lamp 79, white for "take main track," lamp 80, orange, for caution or "call at once" and lamp 81, red, for danger.

In the case of lamps 76 to 79 inclusive an electrical condition in the signal rail which will cause the lighting of a particular lamp in an east bound train will cause the lighting of a different lamp in a west bound train because the arms of the reversing switch are in left hand positions on east bound trains and in right hand positions on west bound trains. Thus the cab circuits for the lamps are such that when alternating and positive direct current is supplied to the signal rails it will cause the lighting of lamp 76 (the clear sign) in an east bound train and of lamp 77 ("no right of way") in a west bound train; when alternating and negative direct current is supplied to the signal rails it will cause the lighting of lamps 76 and 77 in reversed relation, that is to say the lighting of lamp 77 in an east bound train and of lamp 76 in a west bound train; when positive direct current only is supplied to the signal rails it will cause the lighting of lamp 78 ("take siding") in an east bound train and of lamp 79 ("take main track") in a west bound train; and when negative direct current only is supplied to the signal rails it will cause the lighting of lamps 78 and 79 in reversed relation, that is to say the lighting of lamp 79 in an east bound train and the lighting of lamp 78 in a west bound train.

For greater convenience the various electrical conditions of the signal rails and the lamps responsive thereto in east bound and west bound trains are set forth in the following table:

Conditions of signal rail	East bound train	West bound train
A C and D C positive	Lamp 76	Lamp 77
A C and D C negative	Lamp 77	Lamp 76
D C positive only	Lamp 78	Lamp 79
D C negative only	Lamp 79	Lamp 78
A C only	Lamp 80	Lamp 80
De-energized	Lamp 81	Lamp 81

If a clear signal is to be given an east bound train by means of the lamp 76 alternating and positive direct current is supplied to the signal rails and, the arms of the switch S being in left hand position and the signal rail and one of the track rails 1 being assumed as

the opposite terminals of the source of current supply relay A R is energized, relay D R is positively energized, and the armatures 46 to 49 are moved to the left, as shown.

8 Under these conditions a circuit is formed through the lamp 76 as follows: battery 68, wires 69 and 70, polarized armature 47, wire 71, armature 42, wire 98, armature 44, wire 84, polarized armature 49, wire 85, neutral pole 110 of reversing switch, through corresponding arm of said switch in left hand position, contact 111, wire 86, lamp 76, wires 76^a, 57, 66 and 73, polarized armature 46 and wire 74 to other terminal of battery 68.

15 If the train be west bound and its shoe 5 in contact with a signal rail to which alternating and positive direct current is supplied the arms of the switch S will be in right hand position and lamp 77 will glow, the circuit being 20 as follows: battery 68, wires 69 and 70, polarized armature 47, wire 71, armature 42, wire 98, armature 44, wire 84, polarized armature 49, wire 85, neutral pole 110 of reversing switch, through corresponding arm of said 25 switch in right hand position, contact 112, connected wires 113 and 87, lamp 77, wires 77^a, 57, 66 and 73, polarized armature 46 and wire 74 to other terminal of battery 68.

If a clear signal is to be given a west bound 30 train by means of the lamp 76 alternating and negative direct current is supplied to the signal rails and, the arms of the switch S being in right hand position, relay A R is energized, relay D R is negatively energized, and the 35 armatures 46 to 49 are moved to the right. Under these conditions a circuit is formed through the lamp 76 as follows: battery 68, wire 69, polarized armature 46, wires 73, 66, 57 and 76^a, lamp 76, connected wires 86 and 40 114, contact 115 of reversing switch, through corresponding arm of said switch in right hand position, neutral pole 116 of reversing switch, wire 97, polarized armature 49, wire 84, armature 44, wire 98, armature 42, wire 71, polarized armature 47 and wire 74 to the 45 other terminal of battery 68.

If the train be east bound and its shoe 5 in contact with a signal rail to which alternating and negative direct current is supplied the 50 arms of the switch S will be in left hand position and the lamp 77 will glow, the circuit being as follows: battery 68, wire 69, polarized armature 46, wires 73, 66, 57 and 77^a, lamp 77, wire 87, contact 117 of reversing switch, 55 through corresponding switch arm, neutral pole 116 of reversing switch, wire 97, polarized armature 49, wire 84, armature 44, wire 98, armature 42, wire 71, polarized armature 47 and wire 74 to the other terminal of battery 68.

If the signal "take siding" is to be given an east bound train by means of the lamp 78 60 positive direct current only is supplied to the signal rails, the arms of the switch S are in left hand position, and the relay A R is de-

energized because its stick circuit is broken by the raising of the shoe 5 consequent to its contact with the ramp, while relay D R is positively energized and the armatures 46 to 49, inclusive, are moved to the left hand position as shown in the drawings. The circuit thus established may be traced as follows: battery 68, wires 69 and 70, polarized armature 47, wire 71, armature 42 in its lower position, wire 96, armature 45, wire 99, polarized armature 48, wire 100, neutral pole 118 of reversing switch, through the corresponding switch arm in left hand position, contact 119, wire 88, lamp 78, wires 78^a 57, 66 and 73, polarized armature 46 and wire 74 to the 70 other terminal of battery 68.

If the train be west bound and its shoe 5 in contact with a signal rail to which positive direct current only is supplied, the arms of the switch S will be in right hand position and the lamp 79 will glow, the circuit being as follows: battery 68, wires 69 and 70, polarized armature 47, wire 71, armature 42 in the lower position, wire 96, armature 45, wire 99, polarized armature 48, wire 100, neutral pole 118 of 75 reversing switch, through the corresponding switch arm in the right hand position, contact 120 of reversing switch, connected wires 121 and 89, lamp 79, wires 79^a, 57, 66 and 73, polarized armature 46 and wire 74 to the other 80 terminal of battery 68.

If the signal "take siding" is to be given to a west bound train by means of the lamp 78 negative direct current only is supplied to the signal rails, the arms of the switch S are in 85 right hand position, and the relay A R is de-energized because its stick circuit is broken by the raising of the shoe 5 consequent to its contact with the ramp, while relay D R is negatively energized and the armatures 46 to 49, inclusive, are moved to the right hand positions as shown in the drawings. The circuit thus established may be traced as follows: battery 68, wire 69, polarized armature 46, wires 73, 66, 57 and 78^a, lamp 78, connected 90 wires 88 and 122, contact 123 of reversing switch S, through the corresponding arm of 95 said switch in its right hand position, neutral pole 124 of reversing switch, wire 101, polarized armature 48, wire 99, armature 45, wire 96, armature 42 in the lower position, wire 71, armature 47 and wire 74 to the other terminal 100 of battery 68.

If the train be east bound and its shoe 5 in contact with a signal rail to which negative direct current only is supplied, the arms of the switch S will be in left hand position and the lamp 79 will glow, the circuit being as follows: battery 68, wire 69, polarized armature 46, wires 73, 66, 57 and 79^a, lamp 79, wire 89, contact 125 of reversing switch S, through the corresponding switch arm, neutral pole 124 of reversing switch, wire 101, polarized armature 48, wire 99, armature 45, wire 96, armature 42 in the lower position, wire 71, 105 110 115 120 125 130

armature 47 and wire 74 to the other terminal of battery 68.

If alternating current only be supplied to the signal rails, the lamp 80 will be lighted whether the train be east bound or west bound, and whether the armatures 46 to 49, inclusive, are in their left or right hand positions. In this case relay A R is energized but relay D R is de-energized because its stick circuit is broken at the plate 60 by the raising of the shoe 5 by the signal rail. Assuming that the last previous energization of relay D R was negative, so that the armatures 46 to 49, inclusive, are in their right hand positions, the circuit may be traced as follows: battery 68, wire 69, polarized armature 46, wires 73, 66, 57 and 80^a, lamp 80, wire 102, armature 44 in its lower position, wire 98, armature 42, wire 71, polarized armature 47 and wire 74 to the other terminal of battery 68. If, however, the last previous energization of the relay D R was positive, so that the polarized armatures 46 to 49, inclusive, are in their left hand positions, the circuit may be traced as follows: battery 68, wires 69 and 70, polarized armature 47, wire 71, armature 42, wire 98, armature 44 in its lower position, wire 102, lamp 80, wires 80^a, 57, 66, and 73, polarized armature 46 and wire 74 to the other terminal of battery 68.

If the signal rails are de-energized, the lamp 81 will be lighted whether the train be east bound or west bound. In this case the relays A R and D R are both de-energized, the armatures 41 to 45, inclusive, are in their lowered positions and the armatures 46 to 49, inclusive, are in either right or left hand positions accordingly as the previous energization of the relay D R was negative or positive. Assuming that the armatures 46 to 49 are in their left hand positions, as shown, consequent to the last energization of the magnet D R being positive, the circuit thus established may be traced as follows: battery 68, wires 69 and 70, polarized armature 47, wire 71, armature 42 in its lower position, wire 96, armature 45 in its lower position, wire 103, lamp 81, wires 81^a, 57, 66 and 73, polarized armature 46, and wire 74 to the other terminal of battery 68. If, however, the last previous energization of the relay D R was negative, so that the polarized armatures 46 to 49, inclusive, are in their right hand positions, the circuit may be traced as follows: battery 68, wire 69, armature 46, wires 73, 66, 57 and 81^a, lamp 81, wire 103, armature 45 in its lower position, wire 96, armature 42 in its lower position, wire 71, armature 47 and wire 74 to the other terminal of battery 68.

It will thus be seen that for each of the oppositely moving trains there are, in the present embodiment, six operative cab circuit

signal lamps, that is to say the lamps 76 to 79, inclusive, has two circuits controlled by the reversing switch and operative for east and west bound trains respectively. It will further be seen that the signaling current supplied to the rails for causing the lighting of any of the signal lamps 76 to 79, inclusive, selectively differentiates between the lamps of east and west bound trains and co-ordinates the lamps thus selected whereby the signals on opposing trains are appropriate to one another.

In the embodiment disclosed the electrical condition of the signal rails is controlled by switches at the despatcher's office and which are designated generally as 126. There is a switch for each station or block division A—E, etc., of the road and for convenience each switch is shown in the diagram of Figure 1 immediately above its corresponding station. The switches 126 include rocker shafts 127 by which they are mounted and each shaft 127 is connected by a line wire 128 to the signal rails 3—4 of the corresponding station.

The signalling currents are supplied by batteries 129 and 130 and by an alternating current generator 131, all of which are connected by a line wire 132 to a rail of the track 1, the wire 132 being connected to the negative pole of battery 129 and the positive pole of battery 130. At their other poles the batteries 129 and 130 are connected to wires 133 and 134, respectively, in each of which is arranged an impedance coil 135. Magnets 136, one for each station of the road, are bridged across the wire 133 and right hand contacts 137 of the switches 126 and magnets 138 are similarly bridged across the wire 134 and left hand contacts 139 of the switches 126. The generator 131 is connected to the wire 132 by wires 140 and 141 between which is arranged a suitable condenser 142. The other terminal of the generator 131 is connected to a wire 143 and magnets 144, one for each station of the road, are bridged across this wire to right and left hand contacts 145 and 146, respectively, of the switches 126, a condenser 147 being interposed in the wire 148 which connects each magnet 144 and the contacts 145 and 146.

Each switch 126 has rocking movement about the axis of the shaft 127 and longitudinal movement in the direction of said axis. As thrown either to the right or to the left the switch has three positions in its longitudinal range of movement, in the first of which it engages only one or the other of the contacts 137 or 139, in the second of which it engages the pair of contacts 137 and 145 or the pair of contacts 139 and 146 and in the third of which it engages only one or the other of the contacts 145 or 146. The structural details of the switches are shown in Figures 3 and 4. The shaft 127 is mounted

in a front bearing 149 and in rear bearings 150 and 151 which bearings are carried by a suitable supporting bracket 152. The shaft 127 is provided with contact arms 153 and 154 which are insulated from said shaft by bushings 155 and carry a bus bar 156 to which the line wire 128 is connected. The arm 153 is arranged to engage either of the contacts 137 or 139 accordingly as it may be moved to the right or to the left (Figure 1 being considered) and the arm 154 is similarly arranged to engage either of the contacts 145 or 146.

The contacts 137 and 145 comprising the pair at the right hand limit of the pivotal movement of the switch 126 and the contacts 139 and 146 comprising the pair at the left hand limit of the pivotal movement of said switch are of such length and relative arrangement that their engagement by the corresponding switch arms will be as follows in the various operative positions of the switch: Assuming that the switch is in either of its right or left hand position—when the shaft 127 is in its intermediate longitudinal position as shown in Figure 3 both arm 153 and 154 will engage corresponding contacts of either pair, that is to say if the switch is thrown to the right the arm 153 will engage the contact 137 and the arm 154 will engage the contact 145 and if the switch is thrown to the left the arm 153 will engage the contact 139 and the arm 154 will engage the contact 146; when the shaft 127 is in its forward longitudinal position the arm 153 alone will be operative and will engage the contact 137 or 139 as the case may be, the arm 154 being located out of the path of its corresponding contacts 145 and 146; and when the shaft 127 is in its rearward longitudinal position the arm 154 alone will be operative and will engage the contact 145 or 146 as the case may be, the arm 153 being located out of the path of its corresponding contacts 137 and 139.

It is further to be noted that the switch 126 has an intermediate pivotal or neutral position in which the arms 153 and 154 are inoperative; and as shown and preferred the construction is such that when changing from one longitudinal position of the shaft 127 to another longitudinal position of said shaft the switch must first be brought to neutral position and maintained in such position throughout the shifting movement of the shaft, advantages in safety and certainty of operation and control being thereby secured. For these purposes the bearings 150 and 151 are provided with vertical slots 157 and the shaft is provided with a key 158 which, when the switch is in neutral position, alines with said slots and may be moved through them but when the switch is in either right or left hand positions lies athwart them and prevents endwise movement of the shaft. As

shown the shaft 127 is in intermediate longitudinal position and the key 158 is intermediate the bearings 150 and 151. The manipulation of the shaft is provided for by a suitable handle 159 mounted on its front end and if it be desired to move the shaft longitudinally in either direction from the position shown in Figure 3 the switch must first be turned to neutral position whereby to aline the key 158 with the slots 157 upon which the shaft 127 may be moved forward or rearward accordingly as it may be desired to operate only the arm 153 or only the arm 154. In like manner in either of the forward or rearward positions of the shaft the switch must first be moved to neutral position before the shaft can be shifted to intermediate or the opposite extreme longitudinal position.

It is also preferred to provide means for holding the switch against accidental pivotal movement in any longitudinal position of the shaft 127. For this purpose a friction latch may be employed which, as shown and preferred, comprises a spring pressed ball 160 fitted in a socket at the end of an arm 161 secured fast to the shaft 127 and a base 162 having longitudinal grooves 163 corresponding to the right, neutral, and left position of the switch and in which the ball 160 engages, the grooves 163 conforming in length to the range of longitudinal movement of the shaft 127. It will be apparent that the frictional engagement of the ball 160 in any one of the grooves 163 will not interfere with an intentional turning movement of the shaft as effected by the handle 159 but will prevent an accidental turning movement of said shaft.

In the forward longitudinal position of the shaft 127 direct current only will be supplied to the signal rails, positive if the switch be turned to the right and negative if it be turned to the left. In the rearward longitudinal position of the shaft 127 alternating current only will be supplied to the signal rails in either the right or left hand positions of the switch. In the intermediate longitudinal position of the shaft 127 combinations of alternating and direct current will be supplied to the signal rails, alternating and positive direct current if the switch be turned to the right and alternating and negative direct current if the switch be turned to the left.

It is preferred to provide means which is effective in corresponding longitudinal positions of two or more adjacent switches for interlocking them against certain pivotal movements relatively to the neighboring switch or switches. For this purpose interlocking segments 164 are employed. These segments are mounted on the shafts 127 and are each provided with concave lateral edges 165 and a convex intermediate edge 166. To illustrate the cooperation of the interlocking segments it may be assumed that the switches for stations A, B and C are in corresponding, e. g.

intermediate, longitudinal positions in which case the segments 164 prevent any manipulation of these switches which will give clear signals to opposing trains. For example, if the switch for station C be in the left hand position, as shown, to give a clear signal to a west bound train the switch for station B cannot be set in the right hand position to give a clear signal to an east bound train; and in like manner if the switch for station A be set in the right hand position, as shown, to give a clear signal to an east bound train the switch for station B cannot be set in the left hand position to give a clear signal to a west bound train. Where alternate switches are set to give a clear signal to opposing trains, as, for example, the switches for stations A and C in the diagram of Figure 1, the intermediate switch is interlocked in neutral position in which the signal rails of its corresponding block are de-energized to give a danger signal and such switch cannot be moved either to the right or to the left. The segments 164 cooperate in the same way if the adjacent switches are both or all in forward or both or all in rearward positions, that is to say as between two switches arranged to the left and right of one another the switch at the left cannot be turned to its right hand position if the switch at the right be in neutral position or turned to its left hand position if the switch at the left be in neutral position or turned to its right hand position.

If it be desired to supply positive direct current only to the signal rails of a particular station the switch for that station will be shifted to its forward longitudinal position and turned to the right so as to engage its arm 153 with the contact 137. The battery 129 is the source of positive direct current and it may be assumed that the switch of station A has been manipulated as described to supply positive direct current only to the signal rails of that station. Under these conditions a circuit for positive direct signalling current only is established as follows: battery 129, impedance coil 135, wire 133, magnet 136 corresponding to station A, wire 167, contact 137, switch arm 153, bar 156, wire 128, any signal rail at station A, shoe 5, thence through the cab as previously described to a rail of track 1 and by wire 132 to the other terminal of battery 129.

If it be desired to supply negative direct current only to the signal rails of a particular station the switch for that station will be turned to the left in its forward longitudinal position so as to engage its arm 153 with the contact 139. The battery 130 is the source of negative direct current and it may be assumed that the switch of station C has been manipulated as just described to supply negative direct current only to the signal rails

of that station. Under these conditions a circuit for negative direct signalling current only is established as follows: battery 130, wire 132, a rail of track 1, thence through the cab, as previously described, any signal rail of station C, wire 128, bar 156, switch arm 153, contact 139, wire 168, magnet 138 of station C, wire 134, and impedance coil 135 to the opposite terminal of battery 130.

If it be desired to supply alternating current only to the signal rails of a particular station the switch for that station will be turned either to the right or to the left in its rearward longitudinal position. The generator 131 is the source of alternating current and it may be assumed that the switch of station D has been manipulated as just described to supply alternating current only to the signal rails of that station. Under these conditions a circuit for alternating signalling current only is established as follows: generator 131, wire 143, magnet 144 corresponding to station D, condenser 147, wire 148, either of the contacts 145 or 146, according as the switch may be turned to the right or to the left, switch arm 154, bar 156, wire 128, any signal rail at station D, thence through the cab as previously described, a rail of track 1, wires 132, and 141, condenser 142 and wire 140 to the other terminal of generator 131.

If it be desired to supply a combination of direct and alternating current to a particular station the switch for that station is set in its intermediate position and is turned to the right if the direct current be positive and to the left if the direct current be negative. In the diagram of Figure 1 it is assumed that the switch for station E has been manipulated to provide for the supply of alternating and positive direct current to the signal rails of that station in which case its arm 153 engages the contact 137 and its arm 154 engages the contact 145. The respective currents, positive direct and alternating, flow in the two paths previously traced for stations A and D respectively. In like manner if the combination of negative direct and alternating current be supplied to the signal rails, the respective currents, negative direct and alternating, will flow in the two paths previously traced for stations C and D respectively. In any case where a combination of alternating and direct current is supplied to the signal rails the alternating current is prevented from flowing through the batteries 135 and the direct current is prevented from flowing through the generator 131 and the magnets 144 by the condensers 142 and 147.

According to the invention the signals and the movements of trains in relation thereto are recorded at the despatcher's office. For this purpose I preferably employ a chart 169 in the form of a web which is trained over any suitable arrangement of guiding and winding

rollers and which bears regularly spaced transverse or horizontal lines 170 indicative of divisions of time and longitudinal or vertical lines 171 indicative of the stations to which they severally correspond, as indicated in the drawing by the letters A, B, C, D and E. The shaft 172 of the winding roll of said web may be clock driven in any suitable manner but it is preferably geared to a ratchet wheel 173 which is operated by a pawl 174 carried by the armature of an electromagnet 175. Current for the operation of the magnet 175 is supplied by a battery 176 and flows by a wire 177 to the magnet 175, thence by a wire 178 to a clock switch 179, shown conventionally, and thence by a wire 180 to the other terminal of battery 176. The chart 169 is employed in connection with a series of perforating punches which operate adjacent the station lines 171 to record different signals given at the several stations and the movements of the trains in relation to such signals.

The operation of the perforating punches is electrically controlled and according to the invention the circuit which governs the operation of a punch intended to record a particular signal is co-ordinated to the operation of that signal. As shown and preferred this co-ordination is effected by means of the dispatcher's switches in connection with main relays of which three are preferably provided for each station, one being a positive direct current relay D R P and of which the magnet 136 is an element, the second being a negative direct current relay D R N of which the magnet 138 is an element and the third being an alternating current relay A C R of which the magnet 144 is an element. The perforating punches for each station preferably correspond in number to the five electrically energized conditions of the signal rails, the punch 181 being operative when positive direct current only is supplied, the punch 182 when a combination of alternating and positive direct current is supplied, the punch 183 when alternating current only is supplied, the punch 184 when negative direct current is supplied and the punch 185 when a combination of alternating and negative direct current is supplied. The punches 181 to 185 inclusive are respectively operated by magnets 186, 187, 188, 189 and 190, the circuits of which are selected by the main relays D R P, D R N and A C R.

The relay D R P includes three armatures 191, 192 and 193, the relay D R N includes three armatures 194, 195 and 196 and the relay A C R includes a single armature 197. The armatures 191 to 193, 194 to 196 and 197 are raised when their respective operating magnets 136, 138 and 144 are energized and are lowered when the magnets are de-energized.

As a matter of convenience and for a clearer understanding of the diagram of Fig-

ure 1 the punch 183 which operates when alternating current only is supplied to the signal rails is shown as arranged in alignment with the station line 171, the two punches 181 and 182 which operate when positive current is supplied to the signal rails are shown as arranged at the right of the corresponding station line and the two punches 184 and 185 which operate when negative current is supplied to the signal rails are shown at the left of the corresponding station line. In the diagram of Figure 1 it is assumed that the chart 169 is being driven in the upward direction as indicated by the arrow and it may also be assumed that stations A and E are the western and eastern terminals of the line or division thereof. Under such conditions the perforations which are records of the movements of east bound trains will follow a generally oblique path extending downward from left to right of the chart and the perforations which are records of the movements of west bound trains will follow a generally oblique path extending downward from right to left of the chart. In this way the despatcher or official can tell whether the perforations were made by east or west bound trains and the relative location of the perforation on the chart will also indicate the character of signalling current supplied to the train and hence the particular signal which the train received.

Since the circuits for the operating magnets 186 to 190 inclusive may be closed only when one or more of the relays D R P, D R N and A C R are energized and since these relays are energized according to the particular energization of a signal rail only when a shoe 5 is in contact with such rail to close a circuit through the cab it follows that the recording perforation of a particular punch will be made only when the shoe 5 is in contact with a signal rail of the corresponding station but that a punch will be made each time that the shoe 5 passes over a signal rail of that station.

Assuming that positive direct current only is supplied to the signal rails, when the shoe 5 contacts with such rails the circuit of relay D R P of the corresponding station will be closed and the armature 191, 192 and 193 will be raised while the circuits of the other main relays will remain open and their armatures will be lowered. This relation is shown in Figure 1 in connection with the main relays of station A. Under such conditions the operating magnet 186 of the perforating punch 181 will be energized by current supplied by the battery 176 to cause said punch to make a perforation in the chart 169, the circuit being established as follows: battery 176, wires 177, 198, 199, 200 and 216, magnet 186, wire 201, armature 193 in its upper position, wires 202 and 203, armature 197 in its lower posi-

tion, and wires 204 and 180 to the other terminal of battery 176.

Assuming that the combination of alternating and positive direct current only is supplied to the signal rails of a particular station, when the shoe 5 contacts with such rails the circuits of relays D R P and A C R of the corresponding station will be closed and the armatures 191, 192, 193 and 197 will be raised while the circuit of the relay D R N will remain open and the armatures 194, 195 and 196 will be lowered. This relation is shown in Figure 1 in connection with the main relays of station E. Under such conditions the operating magnet 187 of the perforating punch 182 will be energized by current supplied by the battery 176 to cause said punch to make a perforation in the chart 169, the circuit being established as follows: battery 176, wires 177, 198, 199 and 205, magnet 187, wire 206, armature 192 in its upper position, wires 207 and 208, armature 197 in its upper position and wires 204 and 180 to the other terminal of battery 176.

Assuming that alternating current only is supplied to the signal rails, when the shoe 5 contacts with such rails the circuit of relay A C R of the corresponding station will be closed and the armature 197 will be raised while the circuits of the other main relays will remain open and their armatures will be lowered. This relation is shown in Figure 1 in connection with the main relays of station D. Under such conditions the operating magnet 188 of perforating punch 183 will be energized by current supplied by the battery 176 to cause said punch to make a perforation in the chart 169, the circuit established being as follows: battery 176, wires 177, 198 and 209, magnet 188, wire 210, armature 191 in its lower position, wire 211, armature 194 in its lower position, wire 208, armature 197 in its upper position, and wires 204 and 180 to the opposite terminal of battery 176.

Assuming that the combination of alternating and negative direct current is supplied to the signal rails, when the shoe 5 contacts with such rails the circuits of relays D R N and A C R of the corresponding station will be closed and the armatures 194, 195, 196 and 197 will be raised while the circuit of the relay D R P will remain open and the armatures 191, 192 and 193 will be lowered. Under such conditions the operating magnet 190 of the perforating punch 185 will be energized by current supplied by the battery 176 to cause said punch to make a perforation in the chart 169. The circuit thus established may be readily traced in connection with the relays of station E by keeping in mind that the armatures 194, 195 and 196 are assumed to be raised while the armatures 191, 192 and 193 are assumed to be lowered. Such circuit is as follows: battery

176, wires 177, 198, 199 and 212, magnet 190, wire 213, armature 195 in its upper position, wire 208, armature 197 in its upper position and wires 204 and 180 to the other terminal of battery 176.

Assuming that negative direct current only is supplied to the signal rails, when the shoe S contacts with such rails the circuit of relay D R N of the corresponding station will be energized and the armatures 194, 195 and 196 will be raised while the circuits of the other main relays will remain open and their armatures will be lowered. This relation is shown in Figure 1 in connection with the main relays of station C. Under such conditions the operating magnet 189 of the perforating punch 184 will be energized by current supplied by the battery 176 to cause said punch to make a perforation in the chart 169, the circuit being established as follows: battery 176, wires 177, 198, 199, 200 and 214, magnet 189, wire 215, armature 196 in its upper position wire 203, armature 197 in its lower position and wires 204 and 180 to the other terminal of battery 176.

It will be understood that the invention is believed to be of considerable breadth in its particular field and hence that no specific description herein contained is intended to put any limitation upon the scope of the appended claims or to be taken otherwise than for the purpose of exposition.

Having fully described my invention, I claim:

1. In a system of train control, the combination with a vehicle and a trackway of at least three electrical receiving devices on the vehicle, a single unit associated with the trackway and upon which electric current of different characteristics may be impressed, means for severally conditioning said devices in accordance with the electrical condition of said unit, and means operated at a central office for selecting a current of particular characteristic and causing the same to be impressed upon said unit.

2. In a system of train control, the combination with a vehicle and a trackway of sources of electric current of different characteristics, a single unit associated with the trackway and upon which electric currents of different characteristics may be impressed, at least three electrical receiving devices on the vehicle, means for severally conditioning said devices in accordance with the electrical condition of said unit and a central office switch connected to said sources and to said unit for selecting a current of particular characteristic and causing the same to be impressed upon said unit.

3. In a system of train control, the combination with a vehicle and a trackway of sources of electric current of different characteristics, a single unit associated with the trackway and upon which electric currents

- of different characteristics may be impressed, at least three electrical receiving devices on the vehicle, means for severally conditioning said devices in accordance with the electrical condition of said unit, and a central office 5 switch connected to said sources and to said unit for selecting current from one or a combination of said sources and causing the same to be impressed upon said unit.
- 10 4. In a system of train control, the combination with a vehicle and a trackway of electrical receiving devices on the vehicle, a single unit associated with the trackway and upon which electric currents of different characteristics may be impressed, means operative 15 according to the characteristic of the current impressed on said unit for creating at least three distinctive conditions of said receiving devices and means operated at a central office 20 for selecting a current of particular characteristic and causing the same to be impressed upon said unit.
- 25 5. In a system of train control the combination with a vehicle and a trackway of six electrical receiving devices on the vehicle, a single unit upon which currents of different characteristics may be impressed, sources of current of different characteristics, means operated at a central office and connected to 30 said sources and to said unit for impressing a particular electrical condition upon said unit in relation to one or more of said sources and means connected to said unit for conditioning said receiving devices in accordance 35 with the electrical condition of said unit.
- 40 6. In a system of train control the combination with a vehicle and a trackway of electrical receiving devices on the vehicle, a single unit upon which currents of different characteristics may be impressed, sources of current of different characteristics, means operated at a central office and connected to said sources and to said unit for impressing six electrical conditions upon said unit in relation to said 45 sources and means connected to said unit for establishing in accordance with the electrical condition of said unit one of six distinctive conditions of said receiving devices.
- 50 7. In a system of train control the combination with a vehicle of a source of alternating current, a source of positive direct current, a source of negative direct current, a unit upon which current from any one of said sources or conjunctively from the alternating and either 55 of the direct sources may be impressed, means including a single switch operated at a central office and connected to said sources and said unit for selecting current from one or more of said sources and impressing a particular 60 electrical condition upon said unit, electrical receiving devices on the vehicle, and means for distinctively conditioning said receiving devices in accordance with any electrical condition of said unit.
- 65 8. In a system of train control, the combination with a vehicle of electrical receiving devices thereon, a single unit upon which currents of different characteristics may be impressed, means for impressing at least four different electrical conditions upon said unit, 70 means for establishing at least four distinctive conditions of said receiving devices in accordance with the particular electrical condition of said unit, and means for interchanging said conditions of said receiving devices in at least two series, each of at least two conditions, in relation to electrical conditions of said unit in corresponding series, each of corresponding conditions, thereby to provide for bilateral selection of the conditions of said receiving devices in opposing trains.
- 75 9. In a system of train control, the combination with a vehicle of electrical receiving devices thereon, a single unit upon which currents of different characteristics may be impressed, means including a single selecting switch operated at a central office for impressing at least four different electrical conditions upon said unit, means for establishing at least four distinctive conditions of said receiving devices in accordance with the particular electrical condition of said unit, and means for interchanging said conditions of said receiving devices in at least two series, each of at least two conditions in relation to 80 electrical conditions of said unit in corresponding series, each of corresponding conditions, thereby to provide for bilateral selection of the conditions of said receiving devices in opposing trains.
- 85 10. In a system of train control, the combination with a vehicle of at least four electrical receiving devices thereon, a single unit upon which currents of different characteristics may be impressed, means for impressing at least four different electrical conditions upon said unit, means for establishing the operations of the respective receiving devices in accordance with the particular electrical condition of said unit, and means for interchanging said operations in at least two series, each of at least two operations, in relation to 90 electrical conditions of said unit in corresponding series, each of corresponding conditions, thereby to provide for bilateral selection of the operations of said receiving devices in opposing trains.
- 95 11. In a system of train control, the combination with a vehicle of at least four electrical receiving devices thereon, a single unit upon which currents of different characteristics may be impressed, means including a single selecting switch operated at a central office for impressing at least four different electrical conditions upon said unit, means for establishing the operations of the respective receiving devices in accordance with the particular electrical condition of said unit, and means for interchanging said operations in 100 at least two series, each of at least two operations.
- 110 12. In a system of train control, the combination with a vehicle of at least four electrical receiving devices thereon, a single unit upon which currents of different characteristics may be impressed, means including a single selecting switch operated at a central office for impressing at least four different electrical conditions upon said unit, means for establishing the operations of the respective receiving devices in accordance with the particular electrical condition of said unit, and means for interchanging said operations in 115 at least two series, each of at least two operations.
- 120 13. In a system of train control, the combination with a vehicle of at least four electrical receiving devices thereon, a single unit upon which currents of different characteristics may be impressed, means including a single selecting switch operated at a central office for impressing at least four different electrical conditions upon said unit, means for establishing the operations of the respective receiving devices in accordance with the particular electrical condition of said unit, and means for interchanging said operations in 125 at least two series, each of at least two operations.

5   12. In a system of train control, the combination with a vehicle, electrical receiving devices thereon, means for supplying selectively combinations of alternating and positive direct current and of alternating and negative direct current and means for creating, according to the particular combination of alternating and direct current supplied, either of two electrical conditions of said devices including means for interchanging said conditions in relation to the combinations of alternating and direct current.

10   13. In a system of train control, the combination with a vehicle and a trackway, a single unit associated with the trackway and upon which electric current of different characteristics may be impressed, electrical receiving devices on the vehicle, means operative according to the characteristic of the current impressed on said unit for creating at least three conditions of said receiving devices, and central office devices co-ordinated in operation to the several permissible conditions of said receiving devices.

15   14. In a system of train control, the combination with a vehicle and a trackway, of at least three electrical receiving devices thereon, a single unit associated with the trackway and upon which electric current of different characteristics may be impressed, means operative according to the characteristic of the current impressed on said unit for creating at least three conditions of said receiving devices, and central office devices co-ordinated in operation to the several permissible conditions of said receiving devices.

20   15. In a system of train control, the combination with a vehicle of signals therefor operative at a predetermined point in the line of travel, recording devices at a central office, one for each signal, means for selecting and establishing the operation of a particular signal, and means operative upon the movement of the train in relation to such signal for selecting and causing the operation of a corresponding recording device, thereby to record the operation of the signal and the movement of the vehicle in relation thereto.

25   16. In a system of train control, the combination with a vehicle of electrical receiving devices thereon, means located along the line of travel upon which electric current of different characteristics may be impressed, means for conditioning said receiving devices in accordance with the electrical condition of said first named means, recording devices at a central office, one for each condition of said receiving devices, and means for co-ordinating the operation of said recording devices to said receiving devices whereby the

operation of a particular receiving device will be accompanied by the operation of a corresponding recording device.

30   17. In a system of train control, the combination with a vehicle of electrically operated signals thereon, means located along the line of travel upon which electric current of different characteristics may be impressed, means for causing distinctive operations of said signals in accordance with the electrical condition of said first named means, recording devices at a central office, one for each signal, and means for co-ordinating the operation of said recording devices to said signals whereby the operation of a particular signal will be accompanied by the operation of a corresponding recording device.

35   18. In a system of train control, the combination with a vehicle of a unit located along the line of travel and upon which electric currents of different characteristics may be impressed, signals for said vehicle and operative at a predetermined point in the line of travel, recording devices at a central office, one for each signal, means for causing the operation of said recording devices in accordance with the electrical condition of said unit, thereby to record the operation of a particular signal and the movement of the vehicle in relation thereto.

40   19. In a system of train control, the combination with a vehicle of electrical receiving devices thereon, a unit located along the line of travel and upon which electric currents of different characteristics may be impressed, means for conditioning said receiving devices in accordance with the electrical condition of said unit, recording devices at a central office, one for each condition of said receiving devices, and means for causing the operation of said recording devices in accordance with the electrical condition of said unit, thereby to record the operation of a particular receiving device and the movement of the vehicle in relation thereto.

45   20. In a system of train control, the combination with a vehicle of electrically operated signals thereon, a unit located along the line of travel and upon which electric currents of different characteristics may be impressed, means for causing the operation of said signals in accordance with the electrical condition of said unit, recording devices at a central office, one for each signal and means for causing the operation of said recording devices in accordance with the electrical condition of said unit thereby to record the operation of a particular signal and the movement of the vehicle in relation thereto.

50   21. In a system of train control, signals addressed to the engineer and operative at a predetermined point along the line of travel, means at a central office for selec-

- 10 22. In a system of train control, the combination with a vehicle of signals therefor operative at a predetermined point along the line of travel, means at a central office for selectively causing the operation of said signals, devices at a central office and corresponding to the signals for recording movements of the vehicle and means operative when the vehicle moves in relation to a signal point for causing the operation of the recording device corresponding to the signal displayed.
- 15 23. In a system of train control, the combination with a vehicle of signals therefor operative at a predetermined point along the line of travel, means at a central office for selectively causing the operation of said signals, devices at a central office for recording the operations of said signals, one recording device being provided for each signal, and means operative when the vehicle moves in relation to an energized signal for causing the operation of a recording device corresponding to such signal, thereby to record the operation of the signal and the movement 20 of the vehicle in relation thereto.
- 25 24. In a system of train control, the combination with a vehicle of signals therefor operative at a predetermined point along the line of travel, means at a central office for selectively causing the operation of said signals, devices at a central office for recording the operations of said signals, one recording device being provided for each signal, stationary contact means in cooperation with 30 the vehicle and upon which electrical currents of different characteristics may be impressed and means for conditioning and co-ordinating said signals and said recording devices in accordance with the electrical condition of said contact means, thereby to record the operation of a particular signal and the movement of the train in relation thereto.
- 35 25. In a system of train control, the combination of signals addressed to the engineer, recording devices at a central office, one for each signal, and means at a central office for the concomitant selection of the operations of a particular signal and a corresponding recording device.
- 40 26. In a system of train control, the combination of signals addressed to the engineer, recording devices at a central office, one for each signal, and means at a central office for the concomitant selection and co-ordination of the operations of a particular signal and a corresponding recording device.
- 45 27. In a system of train control, the combination with a vehicle of electrical receiving devices thereon, recording devices at a central office, one for each receiving device and means at a central office for the concomitant selection of the operations of a particular receiving device and a corresponding recording device.
- 50 28. In a system of train control, the combination with a vehicle of electrical receiving devices thereon, recording devices at a central office, one for each receiving device and means at a central office for the concomitant selection and co-ordination of the operations of a particular receiving device and a corresponding recording device.
- 55 29. In a system of train control, the combination with a vehicle of at least three electrical receiving devices on the vehicle, means along the line of travel of the vehicle upon which electric currents of different characteristics may be impressed, means for severally conditioning said devices in accordance with the electrical condition of said first named means, central office recording devices, one for each receiving device, means for severally conditioning said recording devices in accordance with the electrical condition of said first named means, and means operated at a central office for selecting a current of particular characteristic and causing the same to be impressed upon said first named means.
- 60 30. In a system of train control, the combination with a vehicle and a trackway of at least three electrical receiving devices on the vehicle, a single unit associated with the trackway and upon which electric current of different characteristics may be impressed, means for severally conditioning said devices in accordance with the electrical condition of said unit, central office recording devices, one for each receiving device, means for severally conditioning said recording devices in accordance with the electrical condition of said unit, and means operated at a central office for selecting a current of particular characteristic and causing the same to be impressed upon said unit.
- 65 31. In a system of train control, the combination with a vehicle, of sources of electric current of different characteristics, means along the line of travel of the vehicle upon which electric currents of different characteristics may be impressed, at least three electrical receiving devices on the vehicle, means for severally conditioning said devices in accordance with the electrical condition of said first named means, central office recording devices, one for each receiving device, means for severally conditioning said recording devices in accordance with the electrical condition of said first named means, and a

- central office switch connected to said sources and to said first named means for selecting a current of particular characteristic and causing the same to be impressed upon said first named means.
- 5 32. In a system of train control, the combination with a vehicle and a trackway of sources of electric current of different characteristics, a single unit associated with the 10 trackway and upon which electric currents of different characteristics may be impressed, at least three electrical receiving devices on the vehicle, means for severally conditioning said devices in accordance with the electrical condition of said unit, central office recording devices, one for each receiving device, means for severally conditioning said recording devices in accordance with the electrical condition of said unit, and a central office switch 15 connected to said sources and to said unit for selecting a current of particular characteristic and causing the same to be impressed upon said unit.
- 20 33. In a system of train control, the combination with a vehicle of sources of electric current of different characteristics, means along the line of travel of the vehicle upon which electric currents of different characteristics may be impressed, at least three electrical receiving devices on the vehicle, means for severally conditioning said devices in accordance with the electrical condition of said first named means, central office recording devices, one for each receiving device, means for 25 severally conditioning said recording devices in accordance with the electrical condition of said first named means, and a central office switch connected to said sources and to said first named means for selecting current from 30 one or a combination of said sources and causing the same to be impressed upon said means.
- 35 34. In a system of train control, the combination with a vehicle and a trackway of sources of electric current of different characteristics, a single unit associated with the trackway and upon which electric currents of different characteristics may be impressed, at least three electrical receiving devices on the vehicle, means for severally conditioning said devices in accordance with the electrical condition of said unit, central office recording devices, one for each receiving device, means for severally conditioning said recording devices in accordance with the electrical condition of said unit, and a central office switch 40 connected to said sources and to said unit for selecting current from one or a combination of said sources and causing the same to be impressed upon said unit.
- 45 35. In a system of train control, the combination with a vehicle of electrical receiving devices thereon, means upon which electric currents of different characteristics may be impressed, means operative according to the 50 characteristics of the current impressed on said first named means for creating at least three distinctive conditions of said receiving devices, central office recording devices, one for each condition of said receiving devices, means for severally conditioning said recording devices in accordance with the electrical condition of said first named means, and means operated at a central office for selecting a current of particular characteristic and causing the same to be impressed upon said first named means. 70
- 55 36. In a system of train control, the combination with a vehicle and a trackway of electrical receiving devices on the vehicle, a single unit associated with the trackway and upon which electric currents of different characteristics may be impressed, means operative according to the characteristic of the current impressed on said unit for creating at least three distinctive conditions of said receiving devices, central office recording devices, one for each condition of said receiving devices, means for severally conditioning said recording devices in accordance with the electrical condition of said unit, and means operated at a central office for selecting a current of particular characteristic and causing the same to be impressed upon said unit. 75
- 60 37. In a system of train control, the combination with a vehicle of sources of current of different characteristics, electrical receiving devices on the vehicle, central office receiving devices, one for each vehicle receiving device, and means for characteristically conditioning and co-ordinating the central office receiving devices and the devices on the vehicle from any one or a combination of said sources, said means including a switch 80 connected to said sources and to said unit for impressing a particular electrical condition upon said unit in relation to one or more of said sources and means connected to said unit for conditioning said receiving and recording devices in accordance 85 with the electrical condition of said unit. 90
- 65 38. In a system of train control, the combination with a vehicle and a trackway of five electrical receiving devices on the vehicle, central office recording devices, one for each receiving device, a single unit upon which currents of different characteristics may be impressed, sources of current of different characteristics, means operated at a central office and connected to said sources and to said unit for impressing a particular electrical condition upon said unit in relation to one or more of said sources and means connected to said unit for conditioning said receiving and recording devices in accordance 95 with the electrical condition of said unit. 100
- 70 39. In a system of train control, the combination with a vehicle and a trackway of electrical receiving devices on the vehicle, a single unit upon which currents of different characteristics may be impressed, sources of current of different characteristics, means operated at a central office and connected to said sources and to said unit for impressing five electrical conditions upon said unit in 105

relation to said sources, means connected to said unit for establishing in accordance with the electrical condition of said unit one of five distinctive conditions of said receiving devices, central office recording devices, one for each condition of said receiving devices, and means also connected to said unit for conditioning said recording devices in accordance with the electrical condition of said unit.

40. In a system of train control, the combination with a vehicle of a source of alternating current, a source of positive direct current, a source of negative direct current, a unit upon which current from any one of said sources or conjunctively from the alternating and either of the direct sources may be impressed, means including a single switch operated at a central office and connected to said sources and said unit for selecting current from one or more of said sources and impressing a particular electrical condition upon said unit, electrical receiving devices on the vehicle, central office recording devices, one for each receiving device, and means for distinctively conditioning said receiving and recording devices in accordance with any electrical condition of said unit.

41. In a system of train control, the combination with a vehicle of electrical receiving devices thereon, means upon which electric current of different characteristics may be impressed, means for creating at least three conditions of said receiving devices in accordance with the particular electrical condition of said first named means, and central office controlling and recording devices co-ordinated in operation to the several permissible conditions of said receiving devices.

42. In a system of train control, the combination with a vehicle and a trackway, a single unit associated with the trackway and upon which electric current of different characteristics may be impressed, electrical receiving devices on the vehicle, means operative according to the characteristic of the current impressed on said unit for creating at least three conditions of said receiving devices, and central office controlling and recording devices co-ordinated in operation to the several permissible conditions of said receiving devices.

43. In a system of train control, the combination with a vehicle of at least three electrical receiving devices thereon, means upon which electric current of different characteristics may be impressed, means for creating at least three conditions of said receiving devices in accordance with the particular electrical condition of said first named means, and central office controlling and recording devices coordinated in operation to the several permissible conditions of said receiving devices.

44. In a system of train control, the com-

bination with a vehicle and a trackway, of at least three electrical receiving devices thereon, a single unit associated with the trackway and upon which electric current of different characteristics may be impressed, means operative according to the characteristic of the current impressed on said unit for creating at least three conditions of said receiving devices, and central office controlling and recording devices co-ordinated in operation to the several permissible conditions of said receiving devices.

45. In a system of train control, the combination with a vehicle of electrical receiving devices thereon, central office recording devices, one for each operative condition of the receiving devices, and central office means for the concomitant selection of a particular operative condition of said receiving devices and of the operation of a corresponding recording device.

46. In a system of train control, the combination with a vehicle of electrical receiving devices thereon, central office recording devices, one for each operative condition of the receiving devices, and central office means for the concomitant selection and co-ordination of a particular operative condition of said receiving devices and of the operation of a corresponding recording device.

47. In a system of train control, the combination with a vehicle and a trackway, the trackway being divided into sections, at least three electrical devices governing the movement of the vehicle, a single unit associated with the trackway and upon which electric currents of different kinds may be impressed, means for severally conditioning said device in accordance with the electrical condition of said unit, and means operated at a central office for selecting a current of a particular kind and causing the same to be impressed upon said unit and at the same time indicate the movement of the vehicle from section to section.

48. In a system of train control, the combination with a vehicle and a trackway divided into sections, of sources of electric current of different kinds, means along the line of travel of the vehicle upon which electric currents of different kinds may be impressed, at least three electrical devices governing the movement of the vehicle over said sections, means for severally conditioning said devices in accordance with the electrical condition of said first named means, means at a central office for indicating the entrance of a vehicle into a section, and a central office switch for connecting to said sources and to said first named means for selecting a current from one or a combination of said sources and causing the same to be impressed upon said means and operably connecting the indicating means with the section.

49. In a system of train control, the com-

5 combination with a vehicle and a trackway, said trackway being divided into sections, electrical governing devices for the vehicle, means upon which electric currents of different kinds may be impressed, means operative according to the kind of current impressed on said first named means for creating at least three distinctive conditions of said receiving devices, a central office indicating 10 means at the central office indicating the entrance of the vehicle upon a section, and means operated at a central office for selecting a current of a particular kind and causing the same to be impressed upon said first 15 named means, said operable means at the central office simultaneously conditioning the indicating means for operation.

50. In a system of train control, the combination with a vehicle moving over a track-way divided into sections, sources of current of different kinds, electrical devices for governing the movement of the vehicle, a central office, means at the central office for indicating the movement of the vehicle into a 20 section, and means for characteristically conditioning the devices governing the movement of the vehicle from any one or a combination of said sources and for indicating the movement of a train into a section, 25 said means including a switch operated at a central office.

51. In a system of train control, the combination with a vehicle and a trackway of six electrical devices for governing the movement of the vehicle, means upon which currents of different kinds may be impressed, sources of current of different kinds, means operated at a central office and connected to said sources and to said means for impressing a particular electrical condition upon 30 said means in relation to one or more of said sources, and means connected with said means for conditioning said electrical devices in accordance with the electrical condition of said means.

45. 52. In a system of train control, the combination with a vehicle and a trackway of six electrical devices governing the movement of the vehicle, a single unit upon which currents of different kinds may be impressed, sources of current of different kinds, means operated at a central office for connecting said sources and said unit for impressing a particular electrical condition upon said 50 unit in relation to one or more of said sources, and means connected to said unit for conditioning said electrical devices in accordance with the electrical condition of said unit.

53. In a system of train control, the combination with a vehicle and a source of alternating current, a source of positive direct current, a source of negative direct current, a unit upon which current from any one of said sources or conjunctively from the alternating and either of the direct sources may

be impressed, means including a single switch operated at a central office and connected to said sources and to said unit for selecting a current from one or more of said sources and impressing a particular electrical condition upon said unit, electrical devices governing the movement of the vehicle, and means for distinctively conditioning said electrical devices in accordance with any electrical condition of said unit.

54. In a system of train control, the combination with a vehicle of electrical devices governing the movement of the vehicle, a single unit upon which currents of different kinds may be impressed, means for impressing at least four different electrical conditions upon said unit, means for establishing at least four distinctive conditions of said electrical devices in accordance with the particular electrical condition of said unit, and means for interchanging said conditions of said electrical devices in at least two series, each of at least two conditions in relation to electrical conditions of said unit in corresponding series, each of conditions, thereby to provide for bilateral selection of the conditions of said electrical devices in opposing trains.

55. In a railway train control and dispatching system, a central office, a single track divided into sections or blocks by sidings or cross-overs, a signal system controlled from said office for the governing of train movements over said sections providing signal protection for either direction of train movements, three or more signals for the governing of trains moving in either one or the other direction over said single track, a switch controlling an electrical circuit at a central office for selecting means for displaying any one of a plurality of signals, said switch when in one position giving a proceed signal to a train moving in one direction over a section and at the same time preventing giving a proceed signal to a train moving over the same section in the opposite direction, and means for indicating at the central office when a train enters a certain section.

56. In a railway train control and dispatching system, a central office, a single track divided into sections or blocks by sidings or cross-overs, a signal system controlled from said office for the governing of train movements over said sections providing signal protection for either direction of train movements, three or more signals for the governing of trains moving in either one or the other direction over said single track, a switch controlling an electrical circuit at a central office for selecting means for displaying any one of a plurality of signals, said switch when in one position giving a proceed signal to a train moving in one direction over a section and at the same time preventing giving a proceed signal to a train moving over the same section in the opposite direction, and means for indi-

cating at the central office the time the train passes a fixed point along the track.

57. In a railway train control and dispatching system, a central office, a single track divided into sections or blocks by sidings or cross-overs, a signal system controlled from said office for the governing of train movements over said sections providing signal protection for either direction of train movements, three or more signals for the governing of trains moving in either one or the other direction over said single track, a switch controlling an electrical circuit at a central office for selecting means for displaying any 10 one of a plurality of signals, said switch when in one position giving a proceed signal to a train moving in one direction over a section and at the same time preventing giving a proceed signal to a train moving over the same 15 section in the opposite direction, and means for indicating at the central office the time consumed by the train in moving over the section.

58. In a railway train control and dispatching system, a central office, a single track divided into sections or blocks by sidings or cross-overs, a signal system controlled from said office for the governing of train movements over said sections providing signal protection for either direction of train movements, three or more signals for the governing of trains moving in either one or the other direction over said single track, a switch controlling an electrical circuit at a central 20 office for selecting means for displaying any one of a plurality of signals, said switch when in one position giving a proceed signal to a train moving in one direction over a section and at the same time preventing giving a proceed signal to a train moving over the same section in the opposite direction, and means for indicating at the central office the progress of the train from section to section.

59. In a railway train control and dispatching system, a central office, a single track divided into sections or blocks by sidings or cross-overs, a signal system controlled from said office for the governing of train movements over said sections providing signal protection for either direction of train movements, three or more signals for the governing of trains moving in either one or the other direction over said single track, a switch controlling an electrical circuit at a central office 25 for selecting means for displaying any one of a plurality of signals, said switch when in one position giving a proceed signal to a train moving in one direction over a section and at the same time preventing giving a proceed signal to a train moving over the same section in the opposite direction, and means for indicating at the central office the direction in which the train is moving.

60. In a railway train control and dispatching system, a central office, a single track di-

vided into sections or blocks by sidings or cross-overs, a signal system controlled from said office for the governing of train movements over said sections providing signal protection for either direction of train movements three or more signals for the governing of trains moving in either one or the other direction over said single track, a switch controlling an electrical circuit at a central office for selecting means for displaying any one of a plurality of signals, said switch when in one position giving a proceed signal to a train moving in one direction over a section and at the same time preventing giving a proceed signal to a train moving over the same section in the opposite direction, and means for indicating at the central office the progress of the train from section to section and the direction in which the train is moving.

61. In a railway train control and dispatching system, a central office, a single track divided into sections or blocks by sidings or cross-overs, a signal system controlled from said office for the governing of train movements over said sections providing signal protection for either direction of train movements, three or more signals for the governing of trains moving in either one or the other direction over said single track, a switch controlling an electrical circuit at a central office for selecting means for displaying any one of a plurality of signals, said switch when in one position giving a proceed signal to a train moving in one direction over a section and at the same time preventing giving a proceed signal to a train moving over the same section in the opposite direction, and means for indicating at the central office the time a train is at a certain section, or the time the train passes a fixed point along the track, or the time consumed by the train in moving over the section, or the progress of the train from section to section, or the direction in which the train is moving, or any combination of such conditions.

62. In a railway train control and dispatching system, a central office, a single track divided into sections or blocks by sidings or cross-overs, a signal system controlled from said office for the governing of train movements over said sections providing signal protection for either direction of train movements more than two signals for the governing of trains moving in either one or the other direction over said single track, a switch controlling an electrical circuit at a central office for selecting means for displaying any one of a plurality of signals, said switch when in one position giving a proceed signal to a train moving in one direction over a section and at the same time preventing giving a proceed signal to a train moving over the same section in the opposite direction, and means for indicating at the central office the time a train is at a certain section.

63. In a railway train control system, a single track provided with a signal system for governing train movements in either direction over the single track, more than two signals for each direction governing the movement of trains, an electrical circuit embracing signal controlling means along the track, an electrical switch in the circuit at a remote point such as a dispatcher's office, an electrical device in the circuit at the dispatcher's office, means, when the electrical switch is placed in one position to display a proceed signal to a train moving in one direction at a certain location and at the same time preventing the display of a proceed signal to a train moving in the opposite direction, at the same location and means controlled by the electrical switch in said circuit located at the dispatcher's office for indicating at the dispatcher's office the time a train is at a certain section, the time the train passes a fixed point along the track, the time consumed by the train in moving over the section, the progress of the train from section to section and the direction in which the train is moving, or any combination of indicating means.

64. In a railway train control system, a central office, a single track divided into sections or blocks provided with a signal system for governing train movements in either direction over the single track, an electrical circuit embracing signal controlling means along the track, one for each section, an electrical switch in the circuit at a remote point such as the central office, an electrical device in the circuit at the central office, one of which indicates proceed, more than two signals for governing the movement of trains on said track, means operative when the electrical switch is placed in one position to display a proceed signal to a train moving in one direction and at the same time preventing the display of a proceed signal to a train moving in the opposite direction, and means controlled by the electrical device in said circuit located at the central office for indicating at said office the progress of the train from section to section.

65. In a railway train control system, a single track railway provided with a signal system for governing train movements in either direction over the single track, more than two signals for the governing of train movements for either direction, means at a central office for selecting, means along the trackway for the display of any one of the signals, and means for indicating at the central office the location of the train on said trackway.

66. In a railway train control system, a single track provided with a signal system for governing train movements in either direction over the single track, three or more signals for each direction governing the movement of trains, an electrical circuit embracing signal controlling means along the track,

an electrical switch in the circuit at a remote point such as a dispatcher's office, an electrical device in the circuit at the dispatcher's office, means including the electrical switch to display any one of the three signals and means when the electrical switch is placed in one position to give a proceed signal to a train moving in one direction, and at the same time and at the same location giving a signal other than proceed to a train operating in the opposite direction.

67. In a railway signal and dispatching system, a track divided into sections over which trains operate in either direction, signals governing the entrance of a train from either direction, a central office, a series of electrical switches at the central office one for each end of a section, means including the electrical switch for giving more than two different signals at an end of a section to a train traveling in one direction and means when a proceed signal is displayed for entering a section to a train traveling in one direction, a signal other than proceed is displayed at the other end of the section to a train moving in the opposite direction.

68. In a railway signal and dispatching system a track divided into sections over which trains operate in either direction, a proceed signal, a take siding signal, and a stop signal, governing the entrance of a train from either direction, a central office, a series of electrical switches at the central office one for each end of a section, means including the electrical switch for giving any one of three signals at an end of a section to a train traveling in one direction and means when a proceed signal is displayed for entering a section to a train traveling in one direction, a signal other than proceed is displayed at the other end of the section to a train moving in the opposite direction.

69. In a railway signal and dispatching system a track divided into sections over which trains operate in either direction, signals governing the entrance of a train from either direction, a central office, a series of electrical switches at the central office one for each end of a section means including the electrical switch for giving more than two different signals at an end of a section to a train traveling in one direction and means when a proceed signal is displayed for entering a section to a train traveling in one direction, a signal other than proceed is displayed at the other end of the section to a train moving in the opposite direction, and means for indicating at the central office the entrance of a train into a section.

70. In a railway signal and dispatching system a track divided into sections over which trains operate in either direction, a proceed signal, a take siding signal and a stop signal governing the entrance of a train from either direction, a central office, a series of

- 5 electrical switches at the central office one for each end of a section, means including the electrical switch for giving any of three signals at an end of a section to a train traveling in one direction and means when a proceed signal is displayed for entering a section to a train traveling in one direction, a signal other than proceed is displayed at the other end of the section to a train moving in 10 the opposite direction, and means for indicating or recording or both at the central office the entrance of a train into a section.

- 15 71. In a railway signal and dispatching system a track divided into sections over which trains operate in either direction, a proceed signal, a take siding signal, and a stop signal governing the entrance of a train from either direction, a central office, a series of electrical switches at the central office for 20 governing train movements over the sections, means including one electrical switch for giving any one of three signals at an end of a section to a train traveling in one direction and means when a proceed signal is displayed for entering a section to a train traveling in one direction, a signal other than proceed is displayed at the other end of the section to a train moving in the opposite direction.

- 25 72. In a system of train control, the combination with a vehicle and a trackway divided into sections, at least three signals governing the movement of the vehicle for each section, means at a central office for selectively causing the operation of said signals, indicating devices at the central office for indicating the movement of a vehicle into one of the sections, and means operative when the vehicle moves in relation to a signal point for 30 causing the operation of the indicating device corresponding to the signal displayed.

- 35 73. In a system of train control, a trackway divided into sections, the combination of at least three signals addressed to the engineer, indicating devices at a central office, one for 40 each section, and means at a central office for the concomitant selection of the operations of a particular signal governing the entrance to a section and a corresponding indicating device.

- 45 74. In a system of train control, the combination with a vehicle of sources of current of different kinds, electrical devices governing the movement of the vehicle, central office indicating devices, one for each vehicle 50 governing device, and means for characteristically conditioning and co-ordinating the central office indicating devices and the devices governing the movement of the vehicle 55 from any one or a combination of said sources, said means including a switch operated at a central office.

- 60 75. In a system of train control, the combination with a vehicle of electrical devices 65 for governing the movement of the vehicle,

means upon which electric current of different kinds may be impressed, means for creating at least three conditions of said electrical devices in accordance with the particular electrical condition of said first named means, and central office controlling and indicating devices co-ordinated in operation to the several permissible conditions of said electrical devices.

70 76. In a system of train control, the combination with a vehicle, electrical devices governing the movement of the vehicle, means for supplying selectively combinations of alternating and positive direct current and of 75 alternating and negative direct current and means for creating, according to the particular combination of alternating and direct current supplied, either of two electrical conditions of said devices including means for interchanging said conditions in relation to the 80 combinations of alternating and direct current.

85 In testimony whereof I affix my signature.
PAUL J. SIMMEN.
